(57) **CLAIM**

The ornamental design for a shoe, as shown and described.

DESCRIPTION

FIG. 1 is a top perspective view of our ornamental design for a shoe;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof; and,

FIG. 8 is an exploded view of the shoe shown in FIG. 1. The broken lines in the drawings depict environmental portions of the shoe that form no part of the claimed design.
